US00D532387S

(12) United States Design Patent (10) Patent No.: US D532,387 S
(45) Date of Patent: * Nov. 21, 2006

(54) INTEGRATED VIDEOCONFERENCING UNIT

(75) Inventors: Branko Lukic, Menlo Park, CA (US);
John Wallace Smith, San Francisco,
CA (US); Jesse Arnold Fourt, Menlo
Park, CA (US); Jonathan I. Kaplan,
Palo Alto, CA (US)

(73) Assignee: LifeSize Communications, Inc.,
Austin, TX (US)

() Term: 14 Years

(21) Appl. No.: 29/217,487

(22) Filed: Nov. 18, 2004

(51) LOC (8) Cl. 14-03

(52) U.S. Cl. D14/126; D14/375

(58) Field of Classification Search D14/125,
D14/126, 127, 128, 129, 133, 374, 375, 376;
348/836, 838, 180, 184, 325, 739; 248/917-924;
345/104, 133, 156, 168, 87, 173; 314/12;
349/1, 2, 11

See application file for complete search history.

(57) CLAIM

The ornamental design for an integrated videoconferencing unit, as shown and described.

DESCRIPTION

FIG. 1 is a front-left-top perspective view thereof;

FIG. 2 is a top view thereof;

FIG. 3 is a front view thereof;

FIG. 4 is a bottom view thereof;

FIG. 5 is a back view thereof;

FIG. 6 is a back-left-top perspective view thereof;

FIG. 7 is a right view thereof; and,

FIG. 8 is a left view thereof.
